UNITED STATES PATENT OFFICE.

JOHN R. MOTES, OF SLOCOMB, ALABAMA.

WHEEL-CHAIR OR WHEEL-CHAIR TRUCK.

1,124,717.

Specification of Letters Patent.

Patented Jan. 12, 1915.

Application filed March 6, 1914. Serial No. 822,937.

To all whom it may concern:

Be it known that I, JOHN R. MOTES, a citizen of the United States of America, and resident of Slocomb, in the county of Geneva and State of Alabama, have invented certain new and useful Improvements in Wheel-Chairs or Wheel-Chair Trucks, of which the following is a specification.

This invention relates to novel means for converting an ordinary rocking chair into an invalid's wheel chair, and the invention has relation primarily to the production of a truck or wheeled device having novel means whereby all its parts may be readily combined within and about the chair without the use of tools and readily dismembered and removed therefrom without the use of tools, and when so attached, forming a complete and dependable rolling chair, retained securely attached to truck against any accidental displacement.

A further object of this invention is to provide a foot rest associated with a chair and wheeled truck and means whereby the foot rest will be suspended from the chair and from the wheeled member, capable of being folded up and out of the way at pleasure, or removed—all without the use of tools.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a vertical sectional view of the chair and wheel support therefor, embodying the invention in the main, and shows application of a chair thereto; Fig. 2 illustrates a plan view of the support, the chair being omitted; Fig. 3 illustrates an enlarged detail view in section of a portion of the support; and Fig. 4 illustrates a detail view of a standard and a means for securing the standard to the axle of the truck.

In these drawings 3 denotes the front axle adapted to be supported by wheels 4, the said front axle having standards 5 to which a sill 6 is connected, whereby the said

sill is supported approximately parallel with and above the axle. Said axle fits into sockets cut into the ends of said standards and the other ends of said standards are embedded into and near the ends of said sill. The sill has a beam 7 connected to it by a strong hinged clamp, attached to the beam with screws and having a T bolt which passes through the beam and is riveted or otherwise secured into the fixed part of said clamp. The hinge joint of said clamp enables the loose part of the clamp to fold on and over the said sill and beam, forcing a cut in sill to fit down into a corresponding cut in said beam receives the bar of a T-bolt through a slot which bar being turned across said slot holds said sill and beam securely and rigidly together, said beam extends rearwardly and terminates in a head 8. There is a notch 9 at the intersection or point of merger of the beam and head, the said notch being adapted for the reception of the rear edge of the seat 10 of a chair 11, which chair may be of the ordinary rocker type as shown. A short bar or sill fits into and across said beam opposite said notch. The hinged clamp comprises the parts 12 and 13 with the end of the T-bolt shown in the middle.

The head 8 has a vertically disposed bearing 14 for the reception of a steering rod 15, the said steering rod having a guiding lever or handle 16 terminating in a slashed thimble fitted with a drop-collar by which the said lever or handle is securely fixed to the rod and by which the rod is controlled and readily rotated for guiding the chair or wheeled truck. The lower end of said steering rod merges into a head 17 terminating in a fork or V-shaped cut for rear wheel and through which bearings are cut for the shaft 18 on which a wheel 20 is mounted. Instead of the guiding wheel described the swivel wheel may be substituted when preferred. The head and nut of this shaft or axle fits into countersinks by which the shaft and wheel are kept into place and both are removed readily by loosening the nut or cap until head and cap are clear of said countersinks.

The truck or wheeled device is shown as having two front wheels and one rear wheel and by manipulating the steering rod the wheel device or chair thereon may be guided and a rocking chair may be mounted thereon and secured without tools. When a chair of

the ordinary rocking type is mounted on the truck, the rear edge of the seat completely fills the notch 9 at the point of merger of the head and beam, and the under surface of the said seat, near the front edge, is caused to rest on the sill, and the front rung 21 is bound or secured to the standards 5 by metal straps 22 each of said straps comprising sections hinged just above the rung 21, and at the lower end of standards 3, the lower hinged portions folds under the standards and against the back of standards where they receive the bars of T-bolts through slots, which bars being turned across said slots, said straps hold chair and truck securely and rigidly together and support the axle from beneath.

A foot rest 23 has rearwardly extending plates or strips 24 connected to hangers 25 and is fixed therein as to height by the screw hooks 28 embedded in said before mentioned sill. A securing device forming an elbow joint consisting of a bolt 26 spur and corresponding shoulders into and against which said spurs rest, hold said foot rest at right angles when open and said elbow joint permits said foot rest to fold upward at pleasure, retaining the foot rest in these different positions of adjustment. Near said elbow joints both strips and hangers have a twist which in the hangers present the edges out and in the strips or plate, bring the sides up in which position said strips or plates receive two boards for the support of the feet. The hangers extend vertically or nearly so between the axle and front rung of chair and the upper end of each hanger has an aperture for the reception of the securing device 28 above described.

By reason of the attachment of the chair to the truck the chair cannot tilt forwardly or rearwardly, nor can it move sidewise, and with the rear wheel turned across, the chair is locked from backward or forward movement and so is made stationary for getting into and out of the chair.

By further reason of this truck, any person who has an ordinary rocking chair can have an inexpensive wheel chair, strong, durable and thoroughly dependable, and one which can be given the form and usefulness of either wheel chair or rocking chair at pleasure, by mounting or dismounting the chair upon and from the wheel truck at pleasure by hand and without the use of tools, and the chair after being used as a wheel chair, being, after it is dismounted from the wheel truck, exactly as before.

The distinctive, distinguishing features of this truck consist in the hinged clamp by which the sill and beam are bound rigidly together, the hinged straps by which the front axle is supported and truck and chair bound together in front, the slashed thimble and drop collar for handle of guiding rod,

the countersinks for securing rear wheel in place, the folding foot rest, and the ready means by which it is attached to chairs without the use of tools, and those features by which no tools are necessary either in mounting the chair thereon or removing it therefrom. The chair is mounted thereon by properly assembling the parts of the truck within and about the chair till the truck is complete.

The trucks are made to the proper dimensions for meeting the requirements of each particular chair to be fitted.

I claim—

1. In a device of the character described, a truck having a head, a beam with a notch at the junction of the head and beam, a sill, means for movably connecting the sill to the beam, standards connected to the sill, metal straps carried by the standards, said metal straps having means for embracing and engaging the rung of a chair and an axle of the truck, and means for securing the straps to the standards, and a sill secured to the beam and extending transversely thereof.

2. In a device of the character described, a truck having a head and beam with a recess at the intersection of the head and beam, a sill, means for connecting the sill to the beam, a short sill across the beam, a forked steering rod terminating in a head, means for detachably mounting rear wheel on the truck, standards with recesses in their lower ends to receive an axle of the truck, and means for binding the standards to the said axle, and a guiding lever for moving the steering rod.

3. In a device of the character described, a truck having a head and beam with a recess at the intersection of the head and beam, a sill, means for connecting the sill to the beam, a hand lever with a slotted thimble termination fitted with a drop collar, a steering rod, a steering wheel fork, standards having recesses in their lower ends to receive the axle of the truck, means for binding the standards to the said axle and simultaneously clamping a rung of the chair, and means for mounting a wheel in the fork.

4. In a device of the character described, a truck having a head and beam with a recess at the intersection of the head and beam, a sill, means for connecting the sill to the beam, a journaled bearing head forming the terminal beam of the said bearing being capable of receiving a steering rod, a steering rod, standards connected to the said standards having recesses in their lower ends to receive the axle of the truck, means for binding the standards to the said axle and simultaneously clamping a rung of the chair, a foot rest, hangers extending from the foot rest, means on the sill for suspending the hangers, said hangers extending be-

tween the rung of the chair and the axle of the truck and being held by the clamping means, and a sill secured to the beam and extending transversely thereof.

5. In a device of the character described, a truck having a head and beam with a recess at the junction of the head and beam, a sill, a metal strap having one end secured to the beam, the said strap extending around 10 the sill, means carried by the beam for securing the opposite end of the strap, a steering rod merging into a head with a steering wheel fork, a steering wheel, means for attaching the steering wheel, a bar and a sill, 15 hangers, means for connecting the hangers to the sill, a foot rest carried by the hangers, standards extending from the sill, said standards having recesses for receiving an axle of the truck, a metal strap on each

standard, each of said metal straps having 20 portions for embracing a rung of a chair, said straps extending under the axle of the truck, and means for securing an end of each strap to a rung, said means comprising a T-bolt, the bar of which engages the outer 25 surface of the strap, said strap having a slot therein to receive said T-bolt, a hand guiding lever having a slotted thimble terminating in a drop collar attached to the steering rod, means for folding foot rest, 30 two front wheels and axle, a rear wheel and means for removably securing the wheels.

In testimony whereof, I affix my signature in the presence of two witnesses.

JOHN R. MOTES.
